CLAIM

We claim an ornamental design for the shim, as shown and described.

DESCRIPTION

FIG. 1 is a perspective view of the shim;
FIG. 2 is a rear elevation view of the shim of FIG. 1;
FIG. 3 is a left side elevation view of the shim of FIG. 1;
FIG. 4 is a top plan view, which is identical to the bottom
plan view, of the shim of FIG. 1;
FIG. 5 is a right side elevation view of the shim of FIG. 1;
and,
FIG. 6 is a front elevation view of the shim of FIG. 1.
The break lines shown in FIGS. 1-6 represent that the shim
is of variable thickness.
The dashed lines are included for illustrating environmental
structure and form no part of the claimed design.
